UNITED STATES PATENT OFFICE.

ELVA CORNELIUS ANDREWS, OF VERMILION, SOUTH DAKOTA.

OPEN-AIR-SLEEPING BED.

1,198,060.

Specification of Letters Patent.

Patented Aug. 18, 1914.

Application filed November 7, 1911. Serial No. 659,073.

To all whom it may concern:

Be it known that I, ELVA CORNELIUS ANDREWS, a citizen of the United States, and resident of the town of Vermilion and county of Clay and State of South Dakota, have invented certain new and useful Improvements in Open-Air-Sleeping Beds, of which the following is a specification.

The object of my invention is to provide a bed for open air sleeping, on which the head of the sleeper may be outside and the body on the inside of the building, whereby the sleeper can gain the advantages of sleeping in the open air and the body may be protected from the cold or other inconveniences of the weather.

A further object is to provide means by which part of the bed may be readily and conveniently moved out of a window or other opening in the wall and as readily withdrawn whereby the sleeper may avoid the storms or other annoyances of the weather or surroundings.

In what it consists, the mode of construction and manner of operation will be fully set out in the following specification when read in connection with the drawings accompanying the same and forming a part hereof.

Figure 1 is a plan view of the frame of the bed. Fig. 2 is a side view with the head projecting through the window. Fig. 3 is a side view with the head withdrawn from the opening in the window. Fig. 4 is a cross section through the mattress, the bed and the base.

Like characters of reference represent corresponding parts in each of the figures.

Having reference to the drawings, 2 represents the frame of the bed which is of rectangular shape and provided with a head rest 4 projecting beyond one end upon which the head of the sleeper rests. The projection 4 is partially surrounded by a removable wind shield 6. Upon this frame is laid the usual mattress 8 or there may be in addition the usual springs or slats which extend the length of the frame including the projection or a mattress may extend to the projection and a separate mattress placed beyond on which is a pillow 10. The frame thus constructed rests upon rollers 5 beneath which is a fixed base 12 having the frame 14 resting upon the legs 15. The legs 15 are preferably in two parts the upper portion 16 being provided with an open-

ing therein into which is inserted a bar 18 with a heavy iron foot 20. The bar 18 projects into the opening in the leg 16 and is held by a thumb screw 22 or any other convenient means. This leg is stayed to the frame by the bars 24. Any other means for adjusting the height of the base may be used.

For the purpose of holding the frame 2 upon the frame 14 and directing its sliding or rolling movement, there are provided two clasps 25 on each side, which grasp the upper surface of the frame 2 and the lower surface of the frame 14 and allows the bed to be moved back and forward on the base 12 or on the rollers.

To prevent the bed from being moved too far through the wall or window 26 there is provided a stop 27 which is attached to the frame 2 and when the bed is withdrawn, engages the frame 14 and prevents any further inward movement.

For the purpose of additional protection against the sun and rain upon the head of the sleeper, there may be provided an awning 28 which is attached to the wall 26 above the window 30.

For convenience in handling there may be attached to the rear end of the frame 2 a ring or hook 35 by which the attendants may withdraw the sleeper from the window and if the attendants desire to carry the patient to some other bed in the room then there may be attached to the frame 2 handles 36 on each side of the frame.

A convenient mode of operating my device is by placing a mattress 8 upon the frame 2 and making the bed thereon in the usual manner, when it is within the house, as shown in Fig. 3. The lower sash 32 of the window is then raised and the frame 2 with the bedding thereon is rolled along upon the rollers 5 or the rollers may be dispensed with and the bed slid along on the base until the stop 27 comes in contact with the wall 26. Then the sleeper lies down upon the bed with his head resting upon the pillow 10 and his head and upper part of his shoulders in the open air and body within the house. The window may then be lowered. Or the party may prepare for sleeping and lie down on the bed within a warm room and then be shoved or shove himself out through the window.

The mode of construction, the material and operation may be widely varied in de-

tail without departing from the spirit and intention of my invention.

Having now described my invention what I claim and desire to secure by Letters Patent is:—

- 5 1. A bed having a reduced section at one end, said reduced section projecting longitudinally from the body of the bed, forming shoulders, and a wind shield secured to the three sides of said reduced section.
- 10 2. In an improvement of the kind described, the combination of a fixed support, a member carried thereby and mounted to be movable longitudinally thereon, and means whereby said member can be moved to project at one end beyond the support and out through an opening in the wall of the room or apartment containing the same, said member having a projection from its bottom to engage the lower edge of the opening and limit such movement.
- 15 3. In an improvement of the kind described, the combination of a fixed support, a frame mounted thereon for longitudinal

movement, guides or retainers secured to the support and engaging the sides of the frame to hold the frame against lateral displacement, a wind shield carried by one end of said frame, a stop projecting from the bottom of said frame adjacent said end, and handles carried by the frame to facilitate the adjustment of the same.

4. In an improvement of the kind described, the combination of a fixed supporting frame mounted thereon for longitudinal movement, means for holding the frame against lateral displacement, a wind shield carried by one end of said frame, a stop projecting from the bottom of the frame to limit its longitudinal movement, and a handle carried by the frame to facilitate the adjustment thereof.

In testimony whereof, I affix my signature in the presence of two witnesses.

ELVA CORNELIUS ANDREWS.
